(57) CLAIM

I claim the ornamental design for a banjo, as shown and described.

DESCRIPTION

FIG. 1 is a top front perspective view of my new design for a banjo;

FIG. 2 is a bottom rear perspective view;

FIG. 3 is a front elevation view;

FIG. 4 is a rear elevation view;

FIG. 5 is a left-side elevation view;

FIG. 6 is a right-side elevation view;

FIG. 7 is a top plan view; and,

FIG. 8 is a bottom plan view.

The broken lines represent the portions of the banjo that form no part of the claimed design.
